UNITED STATES PATENT OFFICE

ISIDOR GREENFIELD, OF NEW YORK, N. Y.

HAT LINING

Application filed June 4, 1929. Serial No. 368,399.

This invention relates to an improved hat lining for use in connection with a soft hat but it will of course be understood that it can be used in connection with other types of hats 5 worn by men, as well as women. In connection with ladies' hats as well as men's hats, the lining is to be inserted without sewing or other handiwork and obviously numerous changes in the specific shape, size and materials may be resorted to without departing 10 from the spirit and scope of the invention as claimed hereinafter.

One object of the invention is to so construct this lining that it may be adjusted to 15 fit in hats of different sizes and may be quickly adjusted to assume the proper size and may be securely held in the desired adjustments.

Another object of the invention is to so 20 construct this lining that the portion thereof which fits between the hat and the sweat-band may be provided with a binding strip formed of celluloid or other similar material so that the lining may be easily and quickly put in 25 place and be prevented from readily becoming wrinkled and causing the hat to fit uncomfortably upon the head.

Another object of the invention is to provide a hat lining which may be formed in 30 a stock size and easily and quickly put in place in hats of different sizes by unskilled labor, thus reducing the cost of the hats.

This invention is illustrated in the accompanying drawings, wherein:

35 Figure 1 is a perspective view showing the lining before being adjusted to the desired size.

Figure 2 is a perspective view showing the lining adjusted to the desired size.

40 Figure 3 is a sectional view showing the lining applied to a hat.

Figure 4 is a sectional view taken along the line 4—4 of Figure 1.

45 Figure 5 is a sectional view taken along the line 5—5 of Fig. 1.

This lining is to be used in connection with a conventional structure of hat which is indicated in general by the numeral 1 and will be provided with the usual sweat-band 2.

50 This hat may be of any suitable shape de-

sired and as previously stated will preferably be a soft hat formed of felt or velour. The lining is provided with the usual top 3 which will have its edge portions sewed to the upper edge of the band 4 which forms the 55 sides of the lining. This band 4 and the top 3 will be formed of any suitable material such as silk, satin or any other desired fabric. The band does not have its ends sewed together as can be seen from an inspection of Figure 1 60 and therefore the end portions of the band can be moved into overlapping relation as shown in Fig. 2. Therefore, the band can be adjusted to the proper size of hat in which the lining is to be placed.

65 From an inspection of Fig. 3, it will be seen that when put in place, the band 4 can fit snugly in place between the sweat-band 2 and the side portions of the hat crown without the sweat-band or body of the hat crown being caused to bulge. A bordering or binding strip 5 will preferably be formed of celluloid, but may of course be formed of any suitable material which will be flexible and at the same time have sufficient resiliency to remain flat when secured to the edge portion of the lining. This bordering strip 70 5 will be pasted or otherwise secured to the edge portion of the wall forming band 4 and one end portion of the band 4 will be turned 75 back and have its upper end portion secured by the stitches which secure the band to the top 3. The lower end portion of the turned back end will be secured by means of a clip 6 which will also be formed of celluloid or 80 other suitable material and as shown in Fig. 5 will straddle the wall 4 and strip 5 and be secured by pasting.

85 A similar clip 7 straddles the other end of the band 4 and strip 5 and will have one end 90 portion pasted to the strip 5. The second end portion of the clip 7 will be left free as shown in Fig. 4 so that the end portions of the band 4 can be moved into overlapping relation as shown in Fig. 2 and when adjusted 95 to the desired size the unsecured end portion of the clip 7 pasted to the wall forming strip. Therefore, the end portions of the band 4 will be secured in the desired overlapping relation. The sweat-band of the hat can then 100

be turned and the lining put in place. The sweat-band can then be returned to the normal position and the wall-forming portion of the lining will be firmly held in place between the sweat-band and the sides of the crown of
5 the hat. It will thus be seen that there has been provided a lining for men's and women's hats which has been so constructed that it may be adjusted to the desired size and
10 easily and quickly put in place.

What is claimed is:

A hat lining including a wall-forming strip having its end portions movable into overlapping relation to provide a lining of
15 a predetermined size, a bordering strip secured along the lower edge portion of the wall-forming band, one end portion of the wall-forming band being turned to extend over the end portion of the bordering strip, and securing clips secured to the strip in a position straddling the wall-forming band and end portions of said bordering strip, one of said clips being secured adjacent each end of the strip, one of said clips having a free
20 arm for engaging the second end portion of the bordering strip when the end portions of said wall-forming band are in overlapping relation.

In testimony whereof I affix my signature.
